E. V. COULSTON

METAL DOOR CONSTRUCTION

Filed Oct. 19, 1922

FIG. 1.

FIG. 2.

FIG. 3.

FIG. 4.

INVENTOR:
EARL V. COULSTON
BY *AG. Mertel*,
ATTORNEY.

Patented Apr. 5, 1927.

UNITED STATES PATENT OFFICE.

EARL V. COULSTON, OF ROCK ISLAND, ILLINOIS.

METAL DOOR CONSTRUCTION.

Application filed October 19, 1922. Serial No. 595,480.

My invention relates to door structures and particularly to door structures for use wherever metal doors are desirable, as in stoves, ovens or the like.

5 The object of the invention is to provide a structure simple and economical of construction and efficient in the performance of its functions.

10 The said invention consists of means hereinafter fully described and particularly set forth in the claims.

15 Heretofore it has been customary in constructing doors for ovens or stoves to make an outer peripheral frame of cast iron the central opening of which is filled, for the purposes of lightness and neatness of appearance, with a sheet-metal panel which was often made outwardly convex, also often exteriorly covered or finished with enamel, 20 and was secured to the frame by means of bolts and nuts or screws. Another and flat panel was secured to the inner surface of said frame to cover the hollow space formed by the exterior panel and to impart a smooth 25 and level inner surface to the door. This inner panel was also secured to the frame by bolts and nuts or screws.

30 It will be seen from the above customary method of making these doors, that the frame was made by casting and the sheet-metal parts by shearing or stamping, two different processes of manufacture, a feature which contributed materially to the cost of manufacture. Also that in order to secure 35 the parts, unsightly and projecting bolts and nuts were used or where screws were used, the process of tapping had to be resorted to, which also contributed undesirable expense of manufacture.

40 More specifically, the object of my invention is to provide a door which may be made by the single process of sheet-metal manipulation and dispense entirely with a cast iron frame and with the use of bolts and nuts or screws and their attendant disadvantages.

45 To this end I make the entire door of sheet-metal and secure the different elements to each other at the peripheral portions of the structure by bending the metal of one 50 element over and pressing it upon the other or others.

Other features of my invention will be hereinafter fully described.

55 The annexed drawing and the following description set forth in detail certain means embodying the invention, the described

means, however, constituting but part of the different forms in which the principle of the invention may be applied.

In said annexed drawing:

60 Fig. 1 represents a plan of a stove or oven door embodying my invention.

Fig. 2 represents, upon an enlarged scale, a longitudinal cross-section.

Fig. 3 represents a plan of a modified 65 form, and

Fig. 4 an enlarged longitudinal cross-section of same.

Referring first to the embodiment of my invention illustrated by Figs. 1 and 2, the 70 structure comprises an inner flat sheet-metal wall member 1 of rectangular form, and an outer sheet-metal wall member 2 also of rectangular form but of greater dimensions than member 1. The peripheral portion of 75 member 1 is first bent at right angles to the plane of the sheet, as shown by the dotted lines, Fig. 2, to form a flange 3 of dimensions such that it will snugly receive member 2 when laid therein.

80

Said member 2 is, however, first subjected to a stamping or bending process to form an intermediate convex exterior surface 4 and a surrounding flat peripheral flange 5. Member 2 is then laid upon member 1, as shown 85 in Fig. 2, and the flange 3 bent down over flange 5 and pressed securely thereon, by suitable means, so as to bring the peripheral portions of the two members firmly in contact with and secure them to each other, the 90 intermediate or central portions of the members being separated from each other, as shown.

The above described structure and method 95 of assemblage is suitable for adoption when unenameled sheet-metal is used for the outer member 2.

Should an enameled sheet be used for the outer wall in the above-described structure, the enamel upon the exterior and inwardly 100 from the inner edge of the flange 3, would crack, when said flange is pressed upon such enameled sheet, and unsightly cracks and imperfections in the enamel surface would be produced and would show plainly upon 105 such exterior.

To allow of the use of such enameled sheet and avoid such undesirable results, I adopt a modified structure and mode of operation.

110 In constructing such modified form, I first take a flat unenameled sheet 6, Fig. 4, and form on the back thereof a peripheral rec-

tangular depression 6.' I then take a rectangular unenameled sheet 7 formed with a central rectangular opening 8 and form a flange 9 thereon at right angles thereto, as shown in dotted lines in Fig. 4. The outer enameled sheet-metal wall member 10, similar to the previously described member 2, is then laid on the back of member 7 and the member 6 then laid on the back of member 10 with their peripheral flanges in contact. The flange 9 is then bent over and pressed upon the back of the member 6 and into the depression 6'. The latter is made of a depth substantially equal to the thickness of the member 7, so that the exterior surfaces of the members 6 and 7 will be flush with each other as shown in Fig. 4. The outer portion of member 7 projects inwardly from the edge of the structure, a greater distance than does the inner portion thereof, so that when pressure is exerted upon the entire inner portion, in assembling, any crack or other imperfection on the outer enameled surface produced thereby will be covered up by the inner peripheral portion of said outer part of member 7.

It will be seen from the above that the modified form of door structure is very similar to the first described form, the main difference consisting of making the inner wall member of two parts, instead of one, namely a primary part 6 and a secondary part 7.

It will thus be seen that a strong, durable door composed entirely of sheet-metal is produced, the parts of which are secured to each other without the use of bolts and nuts

or screws. A finished and attractive appearance is thereby imparted to both the exterior and interior of such door.

What I claim is:

1. In a door structure, the combination of a primary inner sheet-metal wall member; a secondary inner sheet-metal wall member; and an outer sheet-metal wall member; said primary inner member being provided with a peripheral depression upon its inner side; said secondary member being bent around the peripheral portions of said primary and outer members to secure same in contact with each other; the inner portion of said secondary member lying in said depression whereby its inner surface is flush with the inner surface of said inner wall member.

2. In a door structure, the combination of a primary inner sheet-metal wall member; a secondary inner sheet-metal wall member; and an outer sheet-metal wall member; said inner member being provided with a peripheral depression upon its inner side; said secondary member being bent around the peripheral portions of said primary and outer members to secure same in contact with each other; the inner portion of said secondary member lying in said depression whereby its inner surface is flush with the inner surface of said inner wall member; the outer portion of said secondary member extending inwardly from the structure's periphery a greater distance upon the outside than upon the inside of said structure.

Signed by me this 2nd day of October, 1922.

EARL V. COULSTON.
